METHOD AND MACHINE FOR USE IN SHAPING UPPERS OVER LASTS

Bernhardt Jorgensen, Marblehead, Mass., assignor to United Shoe Machinery Corporation, Paterson, N. J., a corporation of New Jersey

Application January 14, 1937, Serial No. 120,596

52 Claims.

(Cl. 12—7)

This invention relates to the shaping of uppers over lasts, and is herein illustrated by reference to the pulling over of uppers preparatory to the lasting of their toe ends and other portions, although in various aspects it is not thus limited in its applicability.

In accordance with one of its objects the invention provides a novel pulling-over method whereby the upper is first subjected to lengthwise strain by a pull applied at the margin of its toe end and is then pulled over and fastened to an insole at the sides of the forepart while held under the lengthwise strain, the margin of the toe end of the upper being thereafter released in an unfastened condition. Preferably, as illustrated, the upper is left free at the sides of the forepart until after the completion of the pull at the toe end, so that its side marginal portions may adjust themselves in accordance with the lengthwise strain, after which the upper is drawn tightly over the forepart widthwise and heightwise of the last by gripping and pulling its side margins. To insure substantial uniformity in the straining of the upper lengthwise of the last along both the top and the sides of the last without objectionable distortion of any portion of the upper, the lengthwise pull, as herein shown, is applied all around the end of the toe, the margin of the upper being gripped substantially in a plane throughout the width of the toe end of the last. In accordance, moreover, with the illustrative disclosure the upper at the sides of the forepart is fastened adhesively to the insole, as is convenient in operating on shoes portions, at least, of which are lasted with adhesive, but it will be understood that the upper may be fastened in a different manner if desired. Such fastening of the upper at the sides of the forepart only, especially in operating on shoes of small sizes such as children's shoes, insures that the upper will remain in a satisfactory pulled-over condition until the toe-lasting operation, the lasting operator being relieved of any necessity for disconnecting the pulled-over upper from the insole at the end of the toe prior to that operation.

The invention further provides a machine for use in the practice of the above-described method, comprising a novel organization of means for subjecting an upper to lengthwise strain by a pull applied at its toe end and for pulling over the upper at the sides of the last while it is held under the lengthwise strain. The construction shown comprises a toe gripper which grips the margin of the upper outspread substantially in a plane and is moved lengthwise of the last to pull the upper, and side-gripping and overlaying devices which thereafter grip the upper at the sides of the forepart and pull it heightwise of the last and inwardly over the insole and press its margin into position to adhere to the insole while the upper

is held under strain by the toe gripper. Conveniently and in accordance with one of the novel features of the invention the construction is such that the toe gripper and the devices at the sides of the forepart are operated by the same member, herein shown as a treadle-operated rod, which is movable first to operate the toe gripper and is thereafter movable to operate the side-gripping and overlaying devices, mechanism being provided for connecting these devices to the rod only upon return of the latter toward starting position after operating the toe gripper. To cause the toe gripper to hold the upper under lengthwise strain it is locked against retractive movement by a device which is movable to release it after the upper has been pulled over and fastened at the sides of the forepart.

Various novel features of the invention are also to be recognized in the means provided for pulling the upper over the last and for laying its margin inwardly over the insole at each side of the forepart, whether such means be arranged to act on that particular portion of a shoe or on some other portion. The construction shown comprises a gripper mounted for swinging movement heightwise of the last and an operating lever connected by a link to one of the gripper jaws to effect first a relative upper-gripping movement of the jaws and then a swinging movement of the gripper to pull the upper, the lever and the link serving as a toggle device movable to a substantially straightened position in thus operating the gripper. The gripper, moreover, is supported on a carrier which is mounted to swing in the same direction as the operating lever to carry the gripper inwardly over the bottom of the last, but is locked against such swinging movement during the pulling of the upper heightwise of the last, the carrier being then released and operated by further movement of the lever. As the gripper is carried inwardly over the bottom of the last it has a component of movement heightwise of the last to cause wiping means thereon to press the margin of the upper on the insole. The gripper and the carrier are relatively movable in response to resistance of the shoe to such movement of the gripper heightwise of the last, and the construction shown is further such that in consequence of this relative movement the gripper jaws are caused to relax their grip on the margin of the upper. To insure, moreover, against any objectionable drag of the gripper and its wiping means on the margin of the upper in the return of the parts to starting positions, a device is provided for preventing any reverse relative movement of the gripper and the carrier until after the gripper has been retracted from over the shoe bottom.

The above and other features of the invention, including also novel means for pulling the upper lengthwise of the last and various novel details of

construction and combinations of parts, will now be more particularly described with reference to the accompanying drawings and thereafter pointed out in the claims.

5 In the drawings,

Fig. 1 is a view in left-hand side elevation of a machine in which the invention is embodied, with parts of the structure broken away;

10 Fig. 2 is a view in front elevation of the upper portion of the machine, with parts broken away;

Fig. 3 shows in front elevation the side gripper and parts associated therewith at the left-hand side of the machine, with the parts in the positions which they assume in pulling the upper, 15 the position of the gripper in laying the upper over the insole also being illustrated in broken lines;

Fig. 4 is a view similar to Fig. 3 with the shoe 20 in section, showing also a portion of the side gripper at the right-hand side of the machine, with the parts in the positions which they assume in pressing the margin of the upper upon the insole;

Fig. 5 is a vertical central section from front 25 to rear, with the side gripper at the right-hand side of the machine and portions of the shoe support omitted;

Fig. 6 is a view of the upper portion of the machine in left-hand side elevation, with the 30 side grippers omitted, showing the parts in the positions which they assume when the toe gripper is holding the upper under lengthwise strain; and

Fig. 7 shows a shoe after it has been operated 35 upon by the machine.

The machine includes a column 2 on the upper end of which (Fig. 5) is threaded a ring 4 having fast thereon a plate 6. Mounted on the plate 6 is another plate 8 which serves as a support 40 for the upper-pulling and shoe-supporting means hereinafter described. Vertically movable in openings in the plates 6 and 8 is a rod 10 controlled by a treadle 12 (Fig. 1) mounted on a pin 14 on the base of the machine, this rod being movable upwardly by the treadle against the resistance of a spring 16 to operate the upper-pulling means. The plate 8 and the parts supported thereon are freely rotatable about the rod 10 to permit the shoe and the upper-pulling 45 means to be positioned in any desired relation to the operator.

For supporting the heel end of the last and shoe there is mounted on the plate 8 a block 18 which is adjustable along a guideway in the plate in directions lengthwise of the shoe. The block is held in adjusted position by a spring-pressed pin 20 therein (Fig. 2) arranged to enter any one of a plurality of holes 22 in the plate 8. Vertically adjustable in the block 18 is a post 24 which is held in adjusted position by a spring-pressed pin 26 (Fig. 1) mounted in the block and arranged to enter any one of a plurality of holes 28 in the post. Mounted on a pin 30 at the upper end of the post 24 for tipping movements in directions lengthwise of the shoe is a block 32 in which is secured a pin 34 arranged to enter the spindle hole in the last. A spring-pressed pin 36 mounted in the post 24 has a V-shaped upper end arranged to engage the block 32 in a correspondingly shaped recess in the lower end of the block to determine the normal position of the pin 34 while permitting the pin and the block to tip in directions lengthwise of the shoe. The toe end of the shoe is supported on a rubber toe rest 38 fastened to a holder 40 which

has a depending stem threaded in a vertical opening in a plate 42 fastened to the upper ends of two arms 44 which are integral at their lower ends with the plate 8. By turning the holder 40 the toe rest 38 may accordingly be adjusted either upwardly or downwardly, and it is held in adjusted position by a pin 46 (Fig. 5) having a rounded end arranged to extend normally into a vertical groove 48 in the stem of the holder 40. The pin 46 is held yieldingly in this groove by a 10 leaf spring 50 fast on the plate 42.

For pulling the upper lengthwise of the last there is provided a toe gripper 52 having a pair of upper-gripping jaws 54 and 56. The jaw 54 is fast on a jaw carrier 58 provided with a pair 15 of spaced downwardly extending arms 60 mounted at their lower ends to swing about a shaft 62 rotatable in bearings in the arms 44. The jaw 56 is supported by screws 64 on one arm 66 of a bell-crank lever 68 mounted to swing about a 20 pin 70 which is supported in two spaced ears of the jaw carrier 58. The screws are threaded in the jaw 56 and extend through enlarged openings in the arm 66 to permit the jaw to assume a parallel relation to the jaw 54 in gripping 25 upper materials of different thicknesses. For determining the normal or starting position of the gripper each of the arms 60 of the jaw carrier 58 is provided at its lower end with a finger 72 arranged to engage a rod 74 mounted in the 30 arms 44, the gripper being held in the position thus determined by a spring-pressed pin 76 mounted in an extension 78 of one of the arms 60 and engaging the rod 74 on the opposite side thereof from the fingers 72. The bell-crank lever 68 is 35 provided with a depending arm 80 which carries at its lower end a pin 82 arranged to lie in slots formed in the bifurcated upper end of an arm 84 mounted to turn on the shaft 62 between the arms 60. Also mounted on the shaft 62 and secured thereto by a set screw 86 is a bell-crank 40 lever 88 provided with an arm 90 arranged to engage one end of a pin 92 slidingly mounted in the arm 84 and backed up by a spring 94 in the arm, the amount of compression of the spring 45 being adjustable by a hand screw 95. Accordingly, movement of the bell-crank lever 88 in a counterclockwise direction (Fig. 5) serves through the pin 92 and the spring 94 to impart swinging movement to the arm 84 and thereby to swing 50 the bell-crank lever 68 in the direction to carry the jaw 56 toward the jaw 54 to grip the margin of the toe end of the upper materials outspread substantially in a plane, the jaws engaging the materials all around the end of the toe throughout the width of the toe end of the last. A spring 96 connected to a short arm 98 of the bell-crank lever 68 and to a lug 100 on one of the arms 60 tends to swing this bell-crank lever in the direction to raise the jaw 56 and accordingly tends 55 also to swing the arm 84 and the bell-crank lever 88 both in clockwise directions, such movements of the parts being limited by engagement of a shoulder 102 on the bell-crank lever 88 with lugs 104 on the arms 60. It will thus be seen that 60 the toe gripper jaws are normally open and that when the bell-crank lever 88 is swung in a counterclockwise direction as above described it serves first to swing the jaw 56 into upper-gripping 65 position against the resistance of the spring 96. Further movement of the bell-crank lever 88 thereafter in the same direction serves through the spring 94 to impart swinging movement to the arms 60 and the gripper jaw carrier 58 in the direction to pull the upper, the spring yield- 70 75

ing more or less in response to resistance of the upper to the force of the pull. Such swinging movement of the jaw carrier 58 is effected against the resistance of the spring-pressed pin 76, the fingers 72 being carried away from the rod 74 as illustrated in Fig. 6. It will be evident that since the gripping of the upper and the movement of the gripper to pull the upper are both effected by the action of the bell-crank lever 88 on the arm 84, the force with which the upper is gripped by the jaws 54 and 56 increases as the force of the pull on the upper increases. To insure against any slipping of the upper materials in the gripper jaws the jaw 56 is provided with a plurality of short pins 106 arranged to force portions of the upper materials more or less into corresponding depressions 108 in the jaw 54.

The movement of the bell-crank lever 88 to cause the toe gripper to grip and pull the upper as above described is effected by upward movement of the rod 10 when the operator depresses the treadle 12, the upper end of the rod being arranged to engage and act on an arm 110 of the bell-crank lever, as illustrated in Fig. 6. The toe gripper is thereafter maintained in position to hold the upper under lengthwise strain by a latch 112 fast on a shaft 114 which is mounted to turn in bearing members 116 (Fig. 2) secured on the plate 8. The latch 112 has a shoulder 118 which is forced under the end of the arm 110, as soon as the arm is lifted far enough to permit this, by a torsion spring 120 on the shaft 114. The operator is accordingly permitted to release the treadle 12 with the upper still held under tension by the toe gripper. A handle 122 fast on the shaft 114 is used by the operator to withdraw the latch 112 from the arm 110 and thus permit the toe gripper to release the upper and return to its starting position after the operations on the shoe have been completed.

The pull of the upper on the heel end face of the last serves, through the action of the last on the pin 34, to swing the block 32 and the pin in the direction to force the toe end of the last down on the toe rest 38. This tends to prevent upward movement of the forepart of the last when the upper is pulled at the sides of the forepart as hereinafter described. If desired, moreover, the operator may assist with his hands in preventing the forepart of the last from rising. In order to hold the heel end of the last down on the block 32 there is provided an arm 124 (Fig. 2) mounted to swing laterally of the shoe about a pin 126 on the block 18. At its upper end this arm is bent toward the shoe and is formed to provide a presser foot or holdown 128 arranged to engage the heel end of the insole when the arm is swung from its idle position (Fig. 2) into the position in which it is shown in Fig. 6. At its lower end the arm 124 is provided with a lug 130 arranged to rest on the top of a horizontal bar 132 which controls the arm. A spring 134 mounted between the block 18 and the arm 124 tends to swing the arm away from the shoe. The bar 132 is pivotally supported on the upper ends of two parallel links 136 and 138 which are pivotally mounted at their lower ends on the plate 8, and the bar is connected by a link 140 to an arm 142 fast on the previously mentioned shaft 62. Accordingly, when this shaft is turned by the bell-crank lever 88 in operating the toe gripper to pull the upper, the arm 142 through the link 140 causes the two parallel links 136 and 138 to swing in directions to raise the bar 132, so that this bar swings the arm 124

to carry the presser foot 128 over and into engagement with the heel end of the insole. It will be understood that when the arm 124 receives its reverse swinging movement upon release of the bell-crank lever 88 by the latch 112, the bar 132 is lowered and the arm 124 is returned to its idle position by the spring 134.

For pulling the upper at the opposite sides of the forepart and for laying its margin inwardly over the insole in position to adhere to the insole there are provided a pair of side grippers 144. Each of these side grippers comprises an upper-gripping jaw 146 mounted on one end of a lever 148 extending laterally of the shoe and a cooperating jaw 150 mounted to swing about a pin 152 on the lever 148 and having an upwardly extending tail portion 154. The jaw 146 consists of a plate having a portion 156 thereof extending in angular relation to its upper-gripping portion to act as a wiper for laying the margin of the upper over the insole and pressing it upon the insole. The jaw has thereon a dovetailed projection 158 curved about an axis extending laterally of the shoe and lying in a correspondingly formed groove in the lever 148 to permit rocking movement of the jaw so that its wiping and pressing portion 156 may adjust itself to the shoe bottom.

Each lever 148 is mounted between its ends to swing in directions heightwise of the shoe about a spindle 160 supported in the upper end of a gripper carrier 162 which is mounted to swing in directions laterally of the shoe about a spindle 164 supported by a plate 166 fast on one of the previously mentioned arms 44. A spring-pressed plunger 168 mounted in the outer arm of the lever 148 and bearing on a shoulder on the carrier 162 tends to swing the lever in the direction to lower the gripper jaws, movement of the lever in that direction being limited by engagement of the head of a screw 170 in the lever with a portion of the carrier 162. In this manner the initial position of the gripper jaws heightwise of the shoe is adjustably determined. A spring 172 connected to the carrier 162 tends to swing the carrier outwardly away from the shoe, the movement of the carrier in this direction being limited by its engagement with the head of a screw 174 threaded in the arm 44.

For operating each side gripper there is mounted to swing about the spindle 164 a bell-crank lever 176. An upwardly extending arm of this bell-crank lever is pivotally connected by a pin 178 to the lower end of a link 180 the upper end of which is pivotally connected to one end of a short link 182, the other end of the link 182 being pivotally connected to the tail portion 154 of the gripper jaw 150. A spring 184 bent around the pin 152 and connected to the link 182 tends to swing the jaw 150 away from the jaw 146, such movement of the jaw 150 being adjustably limited by a stop screw 186 threaded in the tail portion 154 and bearing on the top of the link 182. It will be seen that the upwardly extending arm of the bell-crank lever 176 and the link 180 are in the relation of toggle members and that when the bell-crank lever is swung in the direction to straighten the toggle the link 180 acts through the short link 182 and the screw 186 to swing the jaw 150 toward the jaw 146 and thus to grip the margin of the upper between the two jaws. When the upper resists further closing movement of the jaw 150, the continued straightening of the toggle serves to impart through the link 182 and the screw 186 upward swinging movement to the jaw-

carrying arm of the lever 148 against the resistance of the spring plunger 168 to cause the jaws to pull the upper heightwise of the last, as illustrated in Fig. 3. At the end of this upper-pulling movement the toggle is substantially straight. The lever 148 is locked against reverse swinging movement by a pawl 188 in engagement with ratchet teeth on a plate 190 fast on the lever. The pawl is mounted on the spindle 164 and is urged toward the plate 190 by a spring 192. Initially, however, it is held out of contact with the ratchet teeth by engagement of an end portion of the pin 178 therewith, as illustrated in Fig. 2. The pawl is released by the pin and is forced by the spring 192 into contact with the teeth at the beginning of the operative movement of the bell-crank lever 176.

In the operation of the bell-crank lever 176 to cause the gripper to grip and pull the upper as above described the carrier 162 is locked against swinging movement toward the shoe. For this purpose there is provided a latch 194 in engagement with the head of the previously mentioned screw 174, the latch being fast on a shaft 196 mounted to turn in the carrier 162. Also fast on this shaft is a finger 198, and connected to this finger is a spring 200 which holds the latch normally in operative position, as illustrated in Fig. 2. As the bell-crank lever 176 is operated, one end of the pin 178 moves along a slot 202 in the carrier 162 until, substantially at the end of the upward swinging movement of the gripper, the pin engages the finger 198 and lifts the latch 194, thereby releasing the carrier 162. Substantially at the same time the pin 178 arrives in engagement with the end of a screw 204 in the carrier 162, after which, in the continued movement of the bell-crank lever 176, the pin acts on this screw to swing the carrier toward the shoe against the resistance of the spring 172. In this manner the gripper is carried inwardly over the shoe bottom to lay the margin of the upper over the insole, as illustrated by broken lines in Fig. 3, the pawl 188 as well as the straightened toggle 176, 180 holding the lever 148 against movement in a direction to relax the force of the pull on the upper. It will be evident that by reason of the relation of the gripper jaws to the axis 164 of the swinging carrier 162 the jaws as they are swung inwardly over the shoe bottom have a component of downward movement to press the margin of the upper upon the insole. When such a component of movement of the jaws is no longer possible by reason of resistance of the bottom of the shoe, a relative movement of the carrier 162 and the gripper about the axis 160 occurs as the gripper is moved farther inwardly over the shoe bottom by the carrier. In consequence of this relative movement the link 182 on which the screw 186 bears as to permit an opening movement of the jaw 150 by the spring 184. Accordingly, the gripper opens somewhat in response to pressure of the shoe thereon as it is moved inwardly over the shoe bottom. This permits the margin of the upper to slip readily out of the gripper jaws so that it is wiped throughout its width over the insole by the wiping portion 156 of the jaw 146, as illustrated in Fig. 4. In the above-mentioned relative movement of the carrier 162 and the gripper the pawl 188 slips over one or more additional ratchet teeth on the plate 190, and accordingly upon reverse movement of the bell-crank lever 176 and the carrier 162 in 70 the return of the parts to starting positions the

gripper is lifted from the shoe bottom without any objectionable outward wiping action on the margin of the upper. When the pin 178 arrives nearly at the end of its return movement it engages the pawl 188 and swings the latter out of engagement with the teeth, thus permitting the lever 148 to be returned to its starting position by the spring plunger 168.

For operating both the bell-crank levers 176 to cause the side grippers to grip and pull the upper and to lay its margin over the insole as above described, there is provided a crossbar 206 connected by links 208 to the bell-crank levers, each of these links comprising two relatively adjustable parts having interlocking teeth on their opposed faces and held together by a bolt, as illustrated in Fig. 1. Midway between its opposite ends the crossbar 206 is provided with an opening into which extends the upper end of the previously mentioned treadle-operated rod 10. When this rod is raised to operate the toe gripper in the manner previously described it slides upwardly through the opening in the crossbar without any effect on the crossbar, the latter resting upon the top of the plate 8. In response to a second upward movement of the rod 10, however, the crossbar is raised to operate the side grippers, the crossbar being connected to the rod for this purpose by a locking plate 210 slidably mounted in the crossbar and arranged to enter a groove 212 in the rod. For controlling the plate 210 there is provided a forked arm 214 which extends downwardly at opposite sides of the bell-crank lever 88, the lower ends of the forked portion of this arm lying in slots 215 in the opposite sides of the locking plate 210. At its upper end the arm 214 is secured to an angular block 216 pivotally mounted by means of a pin 218 on a bracket 220 fast on the previously mentioned plate 42. A spring 222 tends to swing this block and the arm 214 in the direction to force the plate 210 into the groove 212 in the rod 10. Initially, however, the plate 210 is maintained in a retracted position, as illustrated in Fig. 5, by a pin 224 carried by the bell-crank lever 88 and engaging edge faces 226 on the arm 214. This permits the rod 10 to be raised to operate the toe gripper without operating the side grippers. In this movement of the rod the pin 224 is carried to a position opposite inclined faces 228 on the arm 214, as illustrated in Fig. 6, so that when the rod 10 is lowered to its starting position the plate 210 will be forced into the groove 212 by the action of the spring 222. Accordingly, when the rod is next raised by the treadle it acts to raise the crossbar 206 and thereby to operate the side grippers, the plate 210 sliding upwardly along the arm 214. The plate 210 is operated to disconnect the rod 10 from the crossbar by the action of the pin 224 on the arm 214 in the return of the bell-crank lever 88 to its starting position upon its release by the latch 112.

Prior to the use of the machine on a shoe the shoe upper materials and an insole will have been assembled on a last and a suitable adhesive will have been applied to the insole and the marginal portions of the upper materials, at least along the sides of the forepart. The shoe materials may or may not be held in assembled relation to the last by one or more fastenings, the drawings showing a child's shoe in which no such fastening is used. After mounting the last with its shoe materials on the pin 34, the operator positions the margin of the toe end of the upper materials outspread substantially in a plane between 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 the toe gripper jaws 54 and 56 and then depresses the treadle 12. As a result of such depression of the treadle the toe gripper grips the margin of the upper and then applies to the upper a lengthwise pull to draw it tightly about the heel end of the last and to stretch it lengthwise as much as required at the top of the forepart and along the sides of the last. At the same time the holdown 124 is swung into operative position over the bottom of the heel end of the shoe. The latch 112 acts automatically to lock the toe gripper against retractive movement, thus permitting the operator to release the treadle while the upper remains under lengthwise strain. As the treadle operated rod 10 returns to its initial position it is connected automatically by the locking plate 210 to the crossbar 206 which operates the side grippers. After arranging the margin of the upper materials at the sides of the forepart between the jaws of the side grippers 144 the operator again depresses the treadle. In this operation the side grippers first grip and pull the upper heightwise of the last, as illustrated in Fig. 3, and are then carried inwardly over the bottom of the last by their swinging carriers 162, the gripper jaws having a component of downward movement toward the bottom of the last. In response to resistance of the shoe to such downward movement of the jaws they relax their pressure on the margin of the upper and thus permit it to slip readily out from between the jaws as the grippers are forced farther inwardly to wipe the upper over the insole and press it more firmly into position to adhere to the insole. The operator then releases the treadle to permit the side grippers to be returned to their starting positions. As the grippers are retracted from over the bottom of the shoe the locking pawls 188 insure that they will be lifted in such manner as to avoid any objectionable outward wiping action on the margin of the upper. After the side grippers have been returned to their starting positions the operator releases the toe gripper by means of the handle 122 and then removes the shoe from the machine. The shoe may thereafter be operated upon, for example, by a lasting machine of the character disclosed in Letters Patent No. 2,075,852, granted on April 6, 1937 upon an application of mine.

Having described the invention, what I claim as new and desire to secure by Letters Patent of the United States is:

1. That improvement in methods of pulling uppers over lasts preparatory to the lasting of their toe ends, which consists in subjecting an upper on a last to lengthwise strain by a pull applied at the margin of its toe end, pulling the upper over the last at the sides of the forepart and fastening it in those locations to an insole on the last while maintaining it under lengthwise strain by the pull at its toe end, and thereafter releasing the margin of the toe end of the upper in an unfastened condition.

2. That improvement in methods of pulling uppers over lasts preparatory to the lasting of their toe ends, which consists in subjecting an upper on a last to lengthwise strain by a pull applied at the margin of its toe end, gripping and pulling the upper over the last at the sides of the forepart after the completion of the pull at its toe end and fastening its margin at the sides of the forepart adhesively to an insole on the last while maintaining the upper under the lengthwise strain by the pull at its toe end, and thereafter releasing the margin of the toe end of the upper in an unfastened condition.

3. That improvement in methods of pulling uppers over lasts preparatory to the lasting of their toe ends, which consists in subjecting an upper on a last to lengthwise strain by a pull applied to its margin substantially all around the end of the toe, thereafter gripping and pulling the upper over the last at the sides of the forepart and fastening its margin in those locations to an insole on the last while maintaining the upper under lengthwise strain by the pull at its toe end, and thereafter releasing the margin of the toe end of the upper in an unfastened condition.

4. That improvement in methods of pulling uppers over lasts preparatory to the lasting of their toe ends, which consists in gripping the margin of the toe end of an upper on a last substantially in a plane throughout the width of the toe end of the last and subjecting the upper to lengthwise strain by a pull applied in that location, thereafter pulling the upper over the last at the sides of the forepart and fastening its margin in those locations to an insole on the last while maintaining the upper under the lengthwise strain by the pull at its toe end, and thereafter releasing the margin of the toe end of the upper in an unfastened condition.

5. In a machine for shaping uppers over lasts, means for subjecting an upper on a last to lengthwise strain by a pull applied at its toe end, and means for gripping and pulling the upper over the last at the sides of the forepart after the completion of the pull at its toe end and for fastening it at the sides of the forepart to an insole on the last while still maintaining the upper under said lengthwise strain by the pull applied at its toe end.

6. In a machine for shaping uppers over lasts, means for subjecting an upper on a last to lengthwise strain by a pull applied at its toe end, and means for thereafter gripping and pulling the upper over the last at the sides of the forepart and for laying its margin in those locations inwardly over an insole on the last and securing it adhesively to the insole while still maintaining the upper under said lengthwise strain by the pull applied at its toe end.

7. In a machine for shaping uppers over lasts, a toe gripper arranged to grip the margin of the toe end of an upper on a last and to subject the upper to lengthwise strain, and side-gripping and overlaying devices arranged to grip the margin of the upper at the sides of the forepart after the completion of the pull by said toe gripper and to pull the upper over the last and lay its margin inwardly over an insole on the last while the upper is still held under tension by the toe gripper.

8. In a machine for shaping uppers over lasts, means for subjecting an upper on a last first to lengthwise strain only by a pull applied at the margin of its toe end, and means for pulling the upper over the last at the sides of the forepart after the completion of the pull at its toe end and for laying its margin at the sides of the forepart inwardly over an insole on the last while still maintaining the upper under said lengthwise strain by the pull applied at its toe end.

9. In a machine for shaping uppers over lasts, a toe gripper arranged to grip the margin of the toe end of an upper on a last and movable in a direction lengthwise of the last to pull the upper, and side-gripping and overlaying devices movable heightwise of the last and inwardly over an insole on the last at the sides of the forepart after the completion of the pulling movement of said toe gripper to pull the upper and lay its margin

inwardly over the insole while the upper is still held under tension by the toe gripper.

10. In a machine for shaping uppers over lasts, a toe gripper arranged to grip the margin of the toe end of an upper on a last substantially in a plane and movable lengthwise of the last to pull the upper, and side-gripping and overlaying devices arranged to grip the margin of the upper at the sides of the forepart and to pull the upper over the last and lay its margin inwardly over an insole on the last while the upper is still held under tension by the toe gripper.

11. In a machine for shaping uppers over lasts, a toe gripper arranged to grip the margin of the toe end of an upper on a last and movable to subject the upper to lengthwise strain, means for locking the toe gripper to maintain the pull on the upper, and side-gripping and overlaying devices movable while the toe gripper is thus locked to pull the upper over the last and lay its margin inwardly over an insole on the last at the sides of the forepart.

12. In a machine for shaping uppers over lasts, a toe gripper arranged to grip the margin of the toe end of an upper on a last and movable to subject the upper to lengthwise strain, side-gripping and overlaying devices arranged to grip the margin of the upper at the sides of the forepart and to pull the upper over the last and lay its margin inwardly over an insole on the last, and means movable by the operator first to operate said toe gripper and then to operate said side-gripping and overlaying devices while the toe gripper is stationary with the upper under lengthwise strain.

13. In a machine for shaping uppers over lasts, a toe gripper arranged to grip the margin of the toe end of an upper on a last and movable to subject the upper to lengthwise strain, side grippers for pulling the upper over the last at the sides thereof, a member movable by the operator to operate said toe gripper, and means for operating the side grippers by another movement of said member only after return of the member toward starting position.

14. In a machine for shaping uppers over lasts, a toe gripper arranged to grip the margin of the toe end of an upper on a last and movable to subject the upper to lengthwise strain, side grippers for pulling the upper over the last at the sides thereof, a member movable by the operator to operate said toe gripper, a device for locking the toe gripper to hold the upper under tension, and means for connecting said member to the side grippers only after return of the member toward starting position for operating the side grippers by another movement of said member.

15. In a machine for shaping uppers over lasts, a toe gripper arranged to grip the margin of the toe end of an upper on a last and movable to subject the upper to lengthwise strain, side grippers for pulling the upper over the last at the sides thereof, a treadle, and means for operating the toe gripper by one depression of said treadle and for thereafter operating the side grippers by a second depression of the treadle after its return toward starting position.

16. In a machine for shaping uppers over lasts, a toe gripper arranged to grip the margin of the toe end of an upper on a last and movable to subject the upper to lengthwise strain, side grippers for pulling the upper over the last at the sides thereof, a treadle-operated rod movable to operate the toe gripper by a depression of the treadle, and means for connecting said rod to

the side grippers after return of the rod and treadle toward starting position for operating the side grippers by a second depression of the treadle.

17. In a machine for shaping uppers over lasts, a toe gripper arranged to grip the margin of the toe end of an upper on a last and movable to subject the upper to lengthwise strain, side grippers for pulling the upper over the last at the sides thereof, a treadle-operated rod movable to operate the toe gripper, and a spring-controlled device arranged to connect said rod to the side grippers for operating them only upon return of the rod toward starting position after operating the toe gripper.

18. In a machine for shaping uppers over lasts, a toe gripper arranged to grip the margin of the toe end of an upper on a last and movable to subject the upper to lengthwise strain, side grippers for pulling the upper over the last at the sides thereof, a crossbar connected to both side grippers for operating them, a treadle-operated rod movable relatively to said crossbar to operate the toe gripper, a spring-controlled device for connecting said rod to the crossbar to operate the crossbar by another movement of the rod, and means for maintaining said device in inoperative position until the rod is moved to operate the toe gripper and for then releasing the device to permit it to connect the rod to the crossbar upon a return movement of the rod.

19. In a machine for shaping uppers over lasts, a pair of jaws for gripping the margin of an upper on a last, a support for said jaws mounted for movement heightwise of the last to pull the upper, and a toggle device movable to a substantially straightened position to effect first a relative movement of said jaws to grip the upper and then to operate said support to pull the upper in response to resistance of the upper to further relative movement of the jaws.

20. In a machine for shaping uppers over lasts, a pair of jaws for gripping the margin of an upper on a last, a support for said jaws mounted for swinging movement heightwise of the last to pull the upper, one of said jaws being pivotally mounted on said support for swinging movement toward the other jaw to grip the upper, a bell-crank lever, and a link connected to one arm of said bell-crank lever and arranged to act on said swinging jaw to effect by the movement of the bell-crank lever first the gripping of the upper by the jaws and then a swinging movement of said support to pull the upper in response to resistance of the upper to further upper-gripping movement of the swinging jaw.

21. In a machine for shaping uppers over lasts, a pair of jaws for gripping the margin of an upper on a last and pulling the upper, one of said jaws being mounted for swinging movement toward the other jaw to grip the upper and having a tail portion at the opposite side of its axis from its upper-gripping portion, a link pivotally connected to said tail portion, a screw threaded in said tail portion and engaging one side of said link, and means for operating said link to impart upper-gripping movement to the swinging jaw through contact of the link with the screw, the screw being adjustable to vary the initial position of the swinging jaw.

22. In a machine for shaping uppers over lasts, a pair of jaws for gripping the margin of an upper on a last, a support for said jaws movable heightwise of the last to pull the upper, one of the jaws being mounted for swinging movement to

- ward the other jaw to grip the upper and having a tail portion at the opposite side of its axis from its upper-gripping portion, a link pivotally connected to said tail portion and extending 5 in a direction transverse to the direction of the pull on the upper, a screw extending heightwise of the last in the tail portion of the swinging jaw and engaging one side of said link, and means connected to said link and movable heightwise 10 of said last to effect first an upper-gripping movement of the swinging jaw and then a movement of said support to pull the upper through contact of the link with said screw.
23. In a machine for shaping uppers over lasts, 15 a gripper for gripping the margin of an upper on a last, a gripper carrier movable to carry said gripper inwardly over the bottom of the last, the gripper being mounted on said carrier for swinging movement heightwise of the last to pull the upper, a reciprocating operating member, and means for first swinging the gripper to pull the upper by movement of said member and for then operating the gripper carrier by further movement 20 of said member in the same direction.
24. In a machine for shaping uppers over lasts, 25 a gripper for gripping the margin of an upper on a last, a gripper carrier movable to carry said gripper inwardly over the bottom of the last and relatively to which the gripper is movable heightwise of the last to pull the upper, an operating member movable in the same direction as said gripper carrier, and means for operating said gripper to pull the upper heightwise of the last by movement of said member, the gripper carrier 30 being movable to carry the gripper inwardly over the bottom of the last in response to further movement of said member.
25. In a machine for shaping uppers over lasts, 35 a gripper for gripping the margin of an upper on a last, a gripper carrier movable to carry said gripper inwardly over the bottom of the last and relatively to which the gripper is movable heightwise of the last to pull the upper, an operating member movable in the same direction as said gripper carrier, and means for operating said gripper to pull the upper heightwise of the last by further movement of said member.
26. In a machine for shaping uppers over lasts, 40 a gripper for gripping the margin of an upper on a last, a gripper carrier movable to carry said gripper inwardly over the bottom of the last and relatively to which the gripper is movable heightwise of the last to pull the upper, an operating member movable in the same direction as said gripper carrier, means for operating said gripper to pull the upper heightwise of the last by movement 45 of said member, a device for locking the gripper carrier against operative movement as the gripper is thus operated, and means for operating said locking device to release the carrier and for then operating the carrier to carry the gripper inwardly over the bottom of the last by further movement of said member.
27. In a machine for shaping uppers over lasts, 50 a gripper for gripping the margin of an upper on a last, a gripper carrier movable to carry said gripper inwardly over the bottom of the last and relatively to which the gripper is movable heightwise of the last to pull the upper, an operating lever, means for operating the gripper to pull the upper heightwise of the last by movement of said lever, the gripper carrier being movable to carry the gripper inwardly over the bottom of the last in response to further movement of said lever, and 55 means for preventing such operation of the gripper carrier until after the operation of the gripper to pull the upper.
28. In a machine for shaping uppers over lasts, 60 a gripper for gripping the margin of an upper on a last, a gripper carrier movable to carry said gripper inwardly over the bottom of the last and relatively to which the gripper is movable heightwise of the last to pull the upper, an operating lever, and a link connection between said lever and the gripper arranged to form with the lever a toggle device movable toward a straightened 65 position for operating the gripper to pull the upper heightwise of the last while the gripper carrier is stationary, the gripper carrier being thereafter movable to carry the gripper inwardly over the bottom of the last by further movement of said lever.
29. In a machine for shaping uppers over lasts, 70 a gripper for gripping the margin of an upper on a last, a gripper carrier movable to carry said gripper inwardly over the bottom of the last and relatively to which the gripper is movable heightwise of the last to pull the upper, a lever mounted for movement in the same direction as said gripper carrier, a link connection between said lever and the gripper arranged to form with the lever a toggle device movable toward a straightened 75 position for operating the gripper to pull the upper heightwise of the last, a device for locking the gripper carrier against operative movement as the gripper is thus operated, and means for operating said locking device to release the carrier and for then operating the carrier to carry the gripper inwardly over the bottom of the last by further movement of said lever.
30. In a machine for shaping uppers over lasts, 80 a pair of jaws for gripping the margin of an upper on a last, a support for said jaws mounted for swinging movement heightwise of the last to pull the upper, a gripper carrier on which said support is thus mounted, said carrier being mounted 85 for swinging movement to carry the jaws inwardly over the bottom of the last, an operating member mounted for swinging movement in the same direction as said carrier, and means for swinging said support heightwise of the last to pull the upper by movement of said member and for thereafter swinging said carrier to carry the jaws inwardly over the bottom of the last by further movement of said member.
31. In a machine for shaping uppers over lasts, 90 a pair of jaws for gripping the margin of an upper on a last, a support for said jaws mounted for movement heightwise of the last to pull the upper, a gripper carrier on which said support is thus mounted, said carrier being movable to carry the 95 jaws inwardly over the bottom of the last, a reciprocating operating member, and means for first effecting relative movement of said jaws to grip the upper by movement of said operating member and for then operating said support to pull the upper by further movement of said member, said gripper carrier being thereafter movable to carry the jaws inwardly over the bottom of the last by still further movement of said member.
32. In a machine for shaping uppers over lasts, 100 a pair of jaws for gripping the margin of an upper on a last, a support for said jaws mounted for movement heightwise of the last to pull the upper, a gripper carrier on which said support is thus mounted, said carrier being movable about an axis 105

to carry the jaws inwardly over the bottom of the last, an operating member mounted for swinging movement in the same direction as said carrier, and means for effecting by movement of said operating member first a relative movement of said jaws to grip the upper, then a movement of said support to pull the upper heightwise of the last, and thereafter a movement of said gripper carrier to carry the jaws inwardly over the bottom of the last.

33. In a machine for shaping uppers over lasts, a gripper for gripping the margin of an upper on a last, a gripper carrier movable to carry said gripper inwardly over the bottom of the last and relatively to which the gripper is movable heightwise of the last to pull the upper, an operating member movable in the same direction as said gripper carrier, means for operating said gripper to pull the upper heightwise of the last by movement of said member and for thereafter operating the gripper carrier by further movement of said member, and a device controlled by said member for locking the gripper against retractive movement heightwise of the last after the pulling of the upper.

34. In a machine for shaping uppers over lasts, a gripper for gripping the margin of an upper on a last, a gripper carrier movable to carry said gripper inwardly over the bottom of the last and relatively to which the gripper is movable heightwise of the last to pull the upper, an operating member movable in the same direction as said gripper carrier, means for operating said gripper to pull the upper heightwise of the last by movement of said member, the gripper carrier being movable to carry the gripper inwardly over the bottom of the last in response to further movement of said member and being thereafter reversely movable to carry the gripper away from over the bottom of the last, and a device arranged to lock said gripper against retractive movement heightwise of the last after the pulling of the upper and to release it only after its movement away from over the bottom of the last.

35. In a machine for shaping uppers over lasts, a gripper for gripping the margin of an upper on a last, a gripper carrier relatively to which the gripper is movable heightwise of the last to pull the upper, said gripper carrier being movable to carry the gripper inwardly over the bottom of the last with a component of movement heightwise of the last toward its bottom face and being thereafter reversely movable to carry the gripper away from over the bottom of the last, and a device arranged to lock said gripper against retractive movement heightwise of the last relatively to the gripper carrier after the pulling of the upper and to hold it thus locked until after its movement away from over the bottom of the last.

36. In a machine for shaping uppers over lasts, a device for gripping an upper and pulling it over a last and for laying the margin of the upper inwardly over and upon an insole on the last, a carrier supporting said device and movable to force it inwardly over the insole while pressing the margin of the upper upon the insole and thereafter reversely movable to carry the device away from over the shoe bottom, said device and carrier being relatively movable in response to pressure of the bottom of the shoe on the device, and means for preventing reverse relative movement of said device and carrier until after the device has been retracted from over the shoe bottom by reverse movement of the carrier.

37. In a machine for shaping uppers over lasts, a device for gripping an upper and pulling it over a last and for laying the margin of the upper inwardly over and upon an insole on the last, a carrier supporting said device and mounted for swinging movement to carry the device inwardly over the insole while imparting to the device a movement heightwise of the last to press the margin of the upper upon the insole, said device and carrier being relatively movable in response to resistance of the shoe to the movement of the device heightwise of the last, and means for preventing reverse relative movement of said device and carrier until after the device has been retracted from over the shoe bottom by a reverse swinging movement of the carrier.

38. In a machine for shaping uppers over lasts, a gripper arranged to grip the margin of an upper and pull the upper over a last and provided with means for wiping the margin of the upper inwardly over an insole on the last, a carrier supporting said gripper and mounted for swinging movement to carry the gripper inwardly over the insole with a component of movement of the gripper heightwise of the last toward its bottom face to press the margin of the upper upon the insole, said gripper and carrier being relatively movable in response to pressure of the bottom of the shoe on the wiping means as the margin of the upper is wiped inwardly, a spring for yieldingly opposing such relative movement, and a device arranged to prevent reverse relative movement of the gripper and carrier until after the gripper has been retracted from over the shoe bottom by a reverse swinging movement of the carrier.

39. In a machine for shaping uppers over lasts, a device for gripping an upper and pulling it over a last and for laying the margin of the upper inwardly over and upon an insole on the last, said device comprising a pair of jaws for gripping the margin of the upper between them, and means for relaxing the pressure of said jaws on the margin of the upper in response to pressure of the bottom of the shoe on said device in the laying of the upper over the insole.

40. In a machine for shaping uppers over lasts, a device for gripping an upper and pulling it over a last and for laying the margin of the upper inwardly over and upon an insole on the last, said device comprising a pair of jaws for gripping the margin of the upper between them, a carrier supporting said device and movable to force it inwardly over the insole while pressing the margin of the upper upon the insole, said device and carrier being relatively movable in response to pressure of the bottom of the shoe on the device in the laying of the upper over the insole, and means for relaxing the pressure of said jaws on the margin of the upper in response to such relative movement of the device and the carrier.

41. In a machine for shaping uppers over lasts, a device for gripping an upper and pulling it over a last and for laying the margin of the upper inwardly over and upon an insole on the last, said device comprising a pair of jaws for gripping the margin of the upper between them, a carrier supporting said device and mounted for swinging movement to carry the device inwardly over the insole with a component of movement thereof heightwise of the last toward its bottom face to press the margin of the upper upon the insole, said device and carrier being relatively movable in response to resistance of the shoe to

such movement of the device heightwise of the last, and mechanism controlling one of said jaws to cause them to release the upper in response to such relative movement of the device and the 5 carrier.

42. In a machine for shaping uppers over lasts, a gripper comprising a pair of jaws for gripping the margin of an upper between them and for pulling the upper over a last, means for moving 10 said gripper inwardly over the bottom of the last with a component of movement thereof heightwise of the last toward its bottom face, and mechanism for effecting a relative opening movement of said jaws in response to resistance of the shoe 15 to such movement of the gripper heightwise of the last.

43. In a machine for shaping uppers over lasts, a gripper comprising a pair of jaws for gripping the margin of an upper between them and for 20 pulling the upper over a last, a carrier supporting said gripper and movable to carry it inwardly over the bottom of the last with a component of movement thereof heightwise of the last toward its bottom face, said gripper and carrier being 25 relatively movable in response to resistance of the shoe to such movement of the gripper heightwise of the last, and mechanism controlling one 30 of said jaws to cause it to relax its pressure on the upper in response to such relative movement of the gripper and the carrier.

44. In a machine for shaping uppers over lasts, a gripper comprising a pair of jaws for gripping the margin of an upper between them and for pulling the upper over a last, a carrier supporting 35 said gripper and mounted for swinging movement to carry the jaws inwardly over the bottom of the last with a component of movement thereof heightwise of the last toward its bottom face, said gripper and carrier being relatively movable 40 in response to resistance of the shoe to such movement of the jaws heightwise of the last as the jaws are carried farther inwardly, and jaw-closing mechanism mounted to swing about the same axis as said carrier and arranged to cause the 45 jaws to relax their pressure on the margin of the upper upon such relative movement of the gripper and the carrier.

45. In a machine for shaping uppers over lasts, a pair of jaws for gripping the toe end of an upper 50 on a last, a jaw carrier mounted for swinging movement lengthwise of the last to cause said jaws to pull the upper, a bell-crank lever mounted on said jaw carrier for moving one of the jaws toward the other to grip the upper, an arm 55 mounted for swinging movement lengthwise of the last to operate said bell-crank lever and also to swing said jaw carrier, a member for operating said arm, and a spring through which the arm is operated by said member.

46. In a machine for shaping uppers over lasts, a pair of jaws for gripping the toe end of an upper 60 on a last, a jaw carrier mounted for swinging movement lengthwise of the last to cause said jaws to pull the upper, a bell-crank lever mounted 65 on said jaw carrier for moving one of the jaws toward the other to grip the upper, an arm mounted for swinging movement lengthwise of the last to operate said bell-crank lever and also to swing said jaw carrier, a second bell-crank 70 lever for operating said arm, and means for operating said second bell-crank lever.

47. In a machine for shaping uppers over lasts, a pair of jaws for gripping the toe end of an

upper on a last, a jaw carrier mounted for swinging movement lengthwise of the last to cause said jaws to pull the upper, a bell-crank lever mounted on said jaw carrier for moving one of the jaws toward the other to grip the upper, an arm 5 mounted for swinging movement lengthwise of the last to operate said bell-crank lever and also to swing said jaw carrier, a second bell-crank lever for operating said arm, a spring for transmitting force yieldingly to the arm from said 10 second bell-crank lever, and a treadle-operated rod movable lengthwise to operate the second bell-crank lever.

48. In a machine for shaping uppers over lasts, a pair of jaws for gripping the toe end of an 15 upper on a last, a jaw carrier mounted for swinging movement lengthwise of the last to cause said jaws to pull the upper, a bell-crank lever mounted on said jaw carrier for moving one of the jaws toward the other to grip the upper, an 20 arm mounted for swinging movement lengthwise of the last to operate said bell-crank lever and also to swing said jaw carrier, a second bell-crank lever for operating said arm, and a device arranged to act on said second bell-crank lever to 25 lock the jaw carrier in upper-pulling position.

49. In a machine for shaping uppers over lasts, a pair of jaws for gripping the toe end of an upper on a last, a jaw carrier mounted for swinging movement lengthwise of the last to cause 30 said jaws to pull the upper, a bell-crank lever mounted on said jaw carrier for moving one of the jaws toward the other to grip the upper, and an arm mounted for swinging movement lengthwise of the last and having a pin-and-slot connection 35 with said bell-crank lever for operating the latter and also for operating the jaw carrier by force transmitted thereto through said bell-crank lever.

50. In a machine for shaping uppers over lasts, 40 a toe gripper arranged to grip the toe end of an upper on a last and movable lengthwise of the last to pull the upper, a bell-crank lever mounted for swinging movement about an axis extending widthwise of the last to operate said toe gripper, 45 a spring for transmitting force from one arm of the bell-crank lever to the toe gripper, and operating means arranged to act on the other arm of said bell-crank lever.

51. In a machine for shaping uppers over lasts, 50 a toe gripper arranged to grip the toe end of an upper on a last positioned bottom upward and movable lengthwise of the last to pull the upper, a bell-crank lever mounted for swinging movement about an axis extending widthwise of the 55 last to operate said toe gripper, and a treadle-operated rod movable upwardly to operate said bell-crank lever.

52. In a machine for shaping uppers over lasts, 60 a toe gripper arranged to grip the toe end of an upper on a last positioned bottom upward and movable lengthwise of the last to pull the upper, a bell-crank lever mounted for swinging movement about an axis extending widthwise of the last to operate said toe gripper, a treadle-operated 65 rod movable upwardly to operate said bell-crank lever, a spring for transmitting force from said bell-crank lever to the toe gripper, and a device arranged to lock said bell-crank lever against retractive movement after operating the 70 toe gripper to maintain the upper under tension.
